INVERTED PRESSURIZED DISPENSERS

Ralph H. Thomas, Rahway, N.J., assignor to Bristol-Myers Company, New York, N.Y., a corporation of Delaware

Application October 20, 1958, Serial No. 768,279

4 Claims. (Cl. 222—162)

This invention pertains to dispensers and more particularly to fluid-pressurized devices for dispensing fluid or pasty materials.

It is presently common practice to dispense materials in the form of liquids, lotions, creams, emulsions and liquid-solid suspensions from devices which contain, in addition to the materials to be dispensed, a pressurizing fluid such as nitrogen or hydrocarbon gases, such as butane and the like which are substantially insoluble in and non-reactive with the material to be dispensed. The most common form taken by such prior art devices is that of a container forming a reservoir for the material to be dispensed and having attached to a valved extremity thereof a dip tube extending into the container to a position adjacent the bottom whereby, when the valve is actuated, fluid pressure exerted upon the surface of the material to be dispensed forces the material outwardly through the dip tube and through a suitable discharge means attached to the valve.

An almost universal defect of such prior art devices is the virtual impossibility of evacuating all of the material from the container. Invariably, a considerable portion of the quantity initially charged into the container is left as a residue after all pressurizing fluid has escaped. This incomplete evacuation is especially serious in dispensing highly viscous materials, in which case the residue frequently comprises as much as from 15 percent to 20 percent of the amount initially charged into the container. This residue, of course, represents an economic loss which should be avoided if possible.

Various forms and modifications of dip tubes have been devised in efforts to obtain complete evacuation of pressurized fluid dispensers, but such devices seldom achieve complete evacuation and invariably add considerable cost to the dispenser. The practice of mounting pressurized fluid dispensers in an inverted position is also known to the prior art. This procedure eliminates the necessity for a dip tube since, in such a position of the dispenser, material is disposed adjacent the valve. However, prior art inverted dispensers are generally of the wall-mounted type and accordingly involve the use of separate mounting means. They frequently also include cumbersome devices to automatically eject the contents upon actuation of the valve in a specified manner as by means of a tooth-brush. Until the present invention, there was absent from the art a convenient, easily manipulatable, self-contained, self-supporting, non-dripping, inverted dispenser.

Therefore, it is an object of the present invention to provide a pressurized dispenser which can be substantially completely evacuated.

It is another object of the invention to provide a device for dispensing fluid or pasty materials from a container supported in an inverted position.

In accordance with the foregoing objects, a preferred embodiment of the present invention comprises a fluid dispenser comprising a container having an open end and a normally closed valve mounted within the open

2

end. A hollow valve stem is secured to the valve and reciprocally movable to open the valve upon movement of the stem inwardly of the container against the valve. The container is charged with a quantity of a material to be dispensed together with a suitable pressurizing fluid. The dispenser also comprises a base member having a cavity or well for slidable reception therein of the container. The base is further provided with an elongated slideaway in which is reciprocally mounted a hollow sleeve open at one end to form a discharge spout and closed at the other end except for an aperture which is registerable with a passageway formed in the base and communicating with the well. Means are provided to detachably secure the valve stem of the container to the base with the bore of the stem in registration with the passageway therein, whereby depression of the container results in the dispensing of the contents of the container through the spout when the sleeve is in an open or discharge position.

Other novel features and advantages of the present invention will become apparent from the following description when considered in conjunction with the accompanying drawings wherein:

Fig. 1 is a cut-a-way side elevation, partially in cross-section, of one embodiment of a dispenser constructed in accordance with the invention and showing the discharge spout in an open position;

Fig. 2 is a cross-sectional view taken along line 2—2 of Fig. 1;

Fig. 3 is a cross-sectional view taken along line 3—3 of Fig. 1;

Fig. 4 is an elevational view similar to that of Fig. 1 but showing the discharge spout in a closed position;

Fig. 5 is a cross-sectional view taken along line 5—5 of Fig. 4, the container being removed for the sake of clarity;

Fig. 6 is an elevational view of the dispenser illustrated in Figs. 1—5;

Fig. 7 is a cross-sectional elevation of a valve suitable for use with a dispenser of the invention;

Fig. 8 is a cross-sectional elevation of a valve stem suitable for use with the valve illustrated in Fig. 7; and

Fig. 9 is a cross-sectional elevation of the assembled valve and valve stem illustrated in Figs. 7 and 8 showing the valve in an open position.

Referring now, in detail, to the drawings and particularly to Fig. 1, the numeral 11 refers generally to a container constituting a reservoir for a fluid or pasty material to be dispensed. The container may take any suitable geometric configuration and may be constructed of any suitable material such as metal, glass, plastic and the like. Containers having a circular horizontal cross-section are generally preferred, primarily because of cost considerations incident to availability and ease of manufacture, as well as ease of operation.

The container may be formed with an open extremity which may be closed by any suitable means, such as a valve support, indicated generally by the numeral 12 (Fig. 7). The support 12 is provided with a peripheral flange 13 which may be crimped about the lip of the open extremity of the container 11 to effect a suitable hermetic seal. Suitable valve means may be mounted upon the valve support 12. One embodiment of a suitable valve is illustrated in Figs. 7—9 wherein the valve supported 12 is provided with a valve casing 14. Upper and lower diaphragms 16 and 17 respectively are inserted within the casing 17 and the latter is then crimped, as at 18, thereby partially deforming the lower valve diaphragm 17 and retaining both diaphragms 16 and 17 within the casing. The lower valve diaphragm 17 is provided with a restricted orifice 19 and a cavity 21 of an expanded diameter communicating therewith. The

70

upper diaphragm 16 is provided with a valve stem cavity 22 opening at one extremity to the exterior of the valve and, at the other extremity, having a portion 23 of expanded diameter. The upper valve diaphragm 16 is further provided with a pair of slits 24 intersecting the stem cavity 22. A hollow valve stem, designated generally by the numeral 26, is provided (Figs. 8 and 9) having a flanged extremity 27 for engagement with the expanded portion 23 of the stem cavity whereby the stem is held securely within the cavity 22. When the stem 26, in an assembled position as illustrated in Fig. 9, is displaced inwardly of the container by the exertion of pressure upon a free extremity 28 thereof, the flanged extremity 27 of the valve stem, by pressing downwardly upon the upper valve diaphragm 16 in the immediate vicinity of the slits 24, deforms the material of the upper diaphragm 16 in such a manner as to open the slits.

The upper valve diaphragm 16 may be formed of any suitable resiliently deformable material which, in an unstressed condition will maintain the slits 24 in a collapsed or closed position and thereby prevent discharge of fluid therethrough. Suitable materials include natural and synthetic rubber and the like. The natural resiliency of such materials causes the valve stem to be returned to a normally closed position upon the release of pressure from the valve stem.

A base or container holder, denoted generally by the numeral 29, comprises a depending skirt 31 for supporting the base and an upright sleeve 32 having an open outer end 33 and defining a well or cavity 34 for the slidable reception therein of the container 11. The base also comprises an elongated housing 36 provided internally with a slideway 37 extending substantially transversely of the upright sleeve 32. The housing 36 is also provided with a passageway 38 communicating with the slideway 37 and with the well 34 and extending substantially along the longitudinal center line of the assembled container and holder 29. A portion of the passageway 38 adjacent the well 34 is of an expanded diameter and is provided internally with suitable means for detachably securing the valve stem 26 therein. For example, the valve stem may be provided adjacent the free extremity thereof with a circumferential groove 39 which, when the stem is inserted within the expanded portion of the passageway 38, snaps into engagement with a correspondingly shaped circumferential ridge 41 on the interior of the passageway. For the purpose of effecting such a connection, and of assuring that such connection is pressure-tight, at least one of the cooperating structures, i.e., valve stem 26 or housing 36 is preferably made of a suitable resiliently deformable material such as a resilient plastic material, for example, polyethylene.

A hollow sleeve, denoted generally by the numeral 42, is slidably mounted within the slideway 37. One extremity of the sleeve 42 is provided with a downwardly extending opening 43 constituting a spout for the discharge of the material to be dispensed. The other extremity of the sleeve 42 is closed except for an orifice 44 which, in an open discharge position of the sleeve 42, is registerable with the passageway 38. A detent 46 is formed on the sleeve 42, depends therefrom and rides in a slot 47 formed in the housing 36. The detent 46 serves the purpose of limiting the travel of the sleeve 42 by engaging the left hand end of the slot 47 in the most extended position of the sleeve (Fig. 1). The extremity of the sleeve 42 adjacent the spout opening 43 is provided with a curved portion 48 which, in the closed position of the sleeve, rests within a correspondingly shaped notch 49 formed in a side wall of the housing 36. An end of the curved portion 48 projects from the housing 36 even in the closed position of the sleeve (Figs. 4 and 6) and thereby provides means for the operator to grasp the sleeve 42 and to retract it to the open position thereof.

In operation, the sleeve 42 is pulled outwardly of the housing 36 until the detent 46 engages the housing 36 at

the end of the slot 47 and the orifice 44 in the sleeve is thereby placed in registration with the passageway 38 and the bore of the hollow valve stem 26. The exertion of pressure by the operator upon an upper end 51 of the container forces the container and the associated upper diaphragm downwardly into the well 34 causing the flanged extremity 27 of the valve stem 26 to exert pressure upon the upper valve diaphragm 16 thereby opening the slits 24 and permitting the pressurized contents of the container to be discharged through the hollow sleeve 42 and out the discharge spout opening 43.

The dimensions of the various cooperating structural elements are determined in such a manner that sufficient spacing is provided between the valve casing 14 and the housing 36 to permit actuation of the valve. Although the natural resiliency of the material forming the upper valve diaphragm 16 is such as to cause the container to return to its original position upon the release of pressure therefrom, a more forceful return action can be achieved by inserting suitable spring means such as a helical spring (not shown) between the container and the housing 36 so that opposite ends of the spring bear upon the housing 36 and the shoulder of the container 11.

The dispensers contemplated by the invention are suitable for dispensing materials of a wide variety of physical forms and are especially suited for dispensing relatively viscous, semi-fluid materials such as toothpastes. When used in dispensing such materials, a toothbrush, denoted by the numeral 52 and illustrated in dashed lines in Fig. 1, may be held under the spout and toothpaste extruded, in ribbon form, upon the brush.

The dispensers of the invention are also highly desirable in the dispensing of hand lotion, hair creams and other cosmetic items which are particularly difficult to evacuate from prior art dispenser devices by reason of their relatively high viscosities. The dispensers of the invention are also useful in the dispensing of liquid or semi-liquid foods and condiments as well as liquid soaps, detergents and the like.

In addition to the mentioned advantages inherent in the dispensers of the invention is the fact that, despite the inverted position of the container, the contents to be dispensed do not, as is the case with many prior art devices, drip from the container during periods of non-use. Dripping is effectively prevented by pushing the sleeve 42 into a closed position during periods of non-use whereupon the discharge spout opening 43 is retracted within the housing 36 and the passageway 38 is closed by the body of the sleeve 42. Consequently, even accidental depression of the container against the valve stem will not result in discharge of the contents of the container.

Moreover, after the initial use of the dispenser, a mass of contents is contained within the housing 36 and adjacent the discharge spout 43 and is consequently ready for immediate discharge when desired.

Manifestly, the invention is not limited to the specific details of construction described and illustrated in connection with the above embodiments thereof. Various modifications and additions may be made by those skilled in the art within the spirit and the scope of the invention.

What is claimed is:

1. A fluid dispenser comprising a valved pressurized container containing a fluid to be dispensed and having a hollow, depressable valve-actuating stem projecting from one end thereof, a container holder comprising a base and an upright sleeve having an open outer end and defining a cavity for slidable reception therein of said container, a housing provided with a slideway extending substantially transversely of said sleeve and a passageway extending substantially along the longitudinal centerline of said support and intersecting said slideway, an elongated hollow spout slidably mounted within said slideway, said spout having a discharge port at one extremity thereof and an aperture registerable with said passageway

adjacent the other extremity thereof, and means to secure said stem to said housing in registration with said passageway whereby movement of said container inwardly of said sleeve actuates said valve to dispense the contents of the container when the aperture of the spout is registered with said passageway.

2. A fluid dispenser comprising a base having a well therein, said base being provided with a passageway communicating with said well, said base being further provided with a slideway communicating at one end thereof with said passageway and at the other end with the exterior of said base, a hollow spout open at one extremity and reciprocably mounted within said slideway, said spout being provided at the other extremity thereof with an aperture registerable, in an open position of the spout, with said passageway, a valved, pressurized, fluid-containing container reciprocably mounted within said well and projecting partially therebeyond, hollow valve-actuating means projecting from said container and secured to said base in registration with said passageway whereby when said container is pushed inwardly of said well and when said spout is in an open position fluid is dispensed from the open extremity thereof.

3. A dispenser comprising a pressurized fluid container, a valve in said container comprising a slotted disc of resiliently deformable material, the slits in said disc being normally closed to fluid egress, a base having a passageway therein, tubular connecting means reciprocably attached at one extremity to said container and bearing against said disc about said slits, said connecting means being secured at the other extremity to said base in registration with said passageway, a slideway within said base and interconnecting with said passageway, a spout

slidably movable within said slideway and having an aperture registerable with said passageway whereby fluid may be dispensed by moving said container relative to said base thereby deforming said disc and spreading said slits to form fluid discharge channels.

4. A dispenser comprising a container containing a paste to be dispensed and a pressurizing fluid, one end of said container being provided with a valve which is normally closed and openable by application thereto of pressure inwardly of the container, a base having formed therein a fluid passageway and a slideway interconnecting therewith and substantially normal thereto, an upright sleeve on said base for slidable reception therein of the valved end of the container, hollow stem means reciprocably attachd to said container and having one extremity bearing upon said valve, the other extremity of said stem being secured to said base about said passageway, an apertured spout slidably mounted in said slideway, said spout being retractable within said base and extendable therebeyond to a dispensing position wherein the aperture of said spout is in registration with said passageway whereby paste may be dispensed by applying pressure to said container.
